[57] CLAIM

The new and ornamental design for a combined ear wax remover and tooth pick, as shown.

DESCRIPTION

FIG. 1 is a perspective view of the combined ear wax remover and tooth pick showing my new design; FIG. 2 is a top plan view of the combined ear wax remover and tooth pick of FIG. 1;

FIG. 3 is a vertical view of the combined ear wax remover and tooth pick of FIGS. 1 and 2;

FIG. 4 is a bottom plan view of the combined ear wax remover and tooth pick of FIGS. 1 through 3; and

FIG. 5 is a view, partly in section, of the combined ear wax remover and tooth pick of FIGS. 1 through 4 taken along lines V—V of FIG. 3.

*Fig. 2.**Fig. 1.**Fig. 3.**Fig. 5.**Fig. 4.*
